UNITED STATES PATENT OFFICE.

HUGH T. NOBLE, OF SEACOME, ENGLAND.

DOOR FOR STEAM-BOILERS.

1,250,629.

Specification of Letters Patent. Patented Dec. 18, 1917.

Application filed December 2, 1916. Serial No. 134,693.

To all whom it may concern:

Be it known that I, HUGH T. NOBLE, a subject of the King of England, resident of Seacome, in the county of Cheshire, England, have made a certain new and useful Invention in Doors for Steam-Boilers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a top plan view of the invention with one half of the outer door section removed.

Fig. 2 is a section of the door on the line 2—2, Fig. 1.

20 Fig. 3 is a similar view with the nuts of the connecting bolts removed, and the key engaged with the central bolt.

Fig. 4 is a similar view with the lower door section in lowered position.

25 The invention has relation to manhole or handhole doors for steam boiler shells, and it consists in the novel construction and combinations of parts, as hereinafter set forth.

30 In the accompanying drawings, illustrating the invention, the numeral 2 designates the boiler shell, having an elliptical opening 3, an annular elliptical reinforcing member 4 being located upon the inner side of said shell and bolted thereto at 5, said member projecting within said opening.

35 The door is composed of inner and outer elliptical sections 6 and 7, the inner section having a marginal flange 8 abutting against a lateral surface of the member 4 through the medium of an annular elliptical washer 9; and a short tubular portion 10 fitting closely within the opening of the reinforcing member and of a length or transverse extent equal to the thickness of said member plus that of said washer, the outer surface of the tubular flange being flush with the outer surface of said member. The inner section is provided with a plurality of short outwardly extending tubular projections or bosses 11, spaced apart from each other and from the member 4, and also of a length or transverse extent equal to the thickness of the said member plus that of said washer

and having their outer surfaces flush with the outer surface of said member.

The outer door section is provided with a marginal flange 12, fitting closely within the opening 3 of the boiler shell and abutting against the outer side of the member 4 through the medium of an annular elliptical washer 13; and with a comparatively long tubular portion 14, in alinement with the tubular flange of the inner door section and of greater thickness than that of the flange 10, to overlap the member 4 and reinforce the flange 12. The outer door section is also provided with a plurality of inward extending tubular bosses or projections 15, spaced apart from each other and from the flange 14 and overlying or in alinement with the tubular bosses of the inner door section, annular washers 16 being located between the tubular bosses of the two door sections.

75 The door sections are connected by transverse bolts 17 fitting within the alined tubular bosses and having exterior nuts 18, the two sections being thereby brought forcibly together to clamp the member 4 between their marginal flanges and to clamp the tubular bosses, through the medium of the washers, the washers of said bosses being thereby compressed and engaging said bolts to pack the bolt holes in a steam and watertight manner.

80 The tubular bosses of each door section are connected with each other and with the tubular flanges of the respective sections by means of cross-ribs 20, said ribs being joined by the tubular bosses and the ribs of the two door sections being spaced apart from each other by the thickness of the washers 16.

85 The tubular flanges of the door sections form a hollow door, having openings to the outer air at 21 through the outer door section, said openings being located between the tubular bosses, and the door being thereby air-cooled, the air being admitted between the cross-ribs of the respective sections spaced apart by the washers 16.

90 In opening the door, the central nut 18 is first removed from its bolt, a key 22 then having its threaded end 23 engaged with an interiorly threaded recess 24 of said bolt, after which a large nut 25 is screwed down upon the thread 26 of the body of said stem,

into contact with the outer door section, the two sections being thereby held securely together, and the other nuts 18 being next removed from their bolts.

5 The key 22 is then grasped by its handle and the nut 25 screwed outwardly upon the key to gradually lower the inner door section until it rests upon the supports 27.

10 The key 22 is finally released from the center bolt, the outer door section removed, and the inner door section turned at right-angles and removed edgewise through the opening of the member 4.

I claim:

15 The combination with a steam boiler having a shell provided with an opening, an inner annular reinforcing member projecting within said opening, and supports spaced apart from said member, of a door comprising an inner section having a marginal flange engaging a lateral surface of said member, and a tubular portion fitting closely within the opening of said member, a plurality of tubular projections, and 20 strengthening ribs connecting said tubular projections with said tubular portion, an 25

outer section having perforations leading to the outer air, a marginal flange fitting closely within the opening of said shell and engaging the other lateral surface of said member, a tubular portion in alinement with and of greater thickness than that of the tubular portion of said inner section and overlapping said reinforcing member, a plurality of tubular projections in alinement 30 with the projections of said inner section, and strengthening ribs connecting said tubular projections with said tubular portion, transverse bolts engaging the tubular projections of said sections and having removable nuts threaded thereon, annular washers located between the marginal flanges of said sections and the lateral surfaces of said reinforcing member, and annular washers located between the tubular projections of 35 said sections.

In testimony whereof I affix my signature, in presence of two witnesses.

HUGH T. NOBLE.

Witnesses:

VICTOR A. STEWART,
JOHN GYERMAN.
